UNITED STATES PATENT OFFICE

172,933

KIDDIE CAR

Richard W. Moran, Van Nuys, Calif.

Application February 1, 1954, Serial No. 28,759

Term of patent 7 years

(Cl. D34—15)

To all whom it may concern:

Be it known that I, Richard W. Moran, a citizen of the United States, residing in Van Nuys, California, have invented a new, original, and ornamental Design for a Kiddie Car, of which the following is a specification, reference being had to the accompanying drawing, forming part thereof;

Fig. 1 is a side elevational view of a kiddie car showing my new design.

Fig. 2 is a top plan view thereof.

Fig. 3 is a front elevational view.

I claim:

The ornamental design for a kiddie car, substantially as shown.
